for the purpose of carrying necktie and other articles of similar character, and the object of the invention is to provide a carrying case which will accommodate a plurality of such tie holders.

The general object of the invention is to provide a carrying case having a plurality of tie holders which are individually removable, and which are held in spaced relation by means of a plurality of hinge members.

Another object is to provide a carrying case which will accommodate a plurality of tie holders which are individually removable, and which are held in spaced relation by means of a plurality of hinge members.

Still another object is to provide a carrying case which will accommodate a plurality of tie holders which are individually removable, and which are held in spaced relation by means of a plurality of hinge members.

UNITED STATES PATENT OFFICE

NECKTIE CARRIER

Anthony A. Baur, Monroe, La.

Application October 28, 1948, Serial No. 57,103

3 Claims. (Cl. 206—7)

1

This invention relates to necktie carriers, and more particularly to an improved, combined carrier and press.

The general object of the invention is to provide a device of this character comprising a carrying case having a plurality of separate, individually removable tie holders assembled therein, each tie holder being in the nature of a press. A specific object is to devise improved means for anchoring the holders in the case, so that they may be readily removed when desired, without the necessity of releasing any fastening device.

Another specific object of the invention is to provide a simple and convenient construction of holder, into and from which a tie may be readily inserted and removed, and which will serve to effectively press the tie so as to keep it smooth and free from wrinkles at all times.

With the above and other objects in view, and to improve generally on the details of such apparatus, the invention consists in the construction, arrangement and combination of parts hereinafter described and claimed, and illustrated in the accompanying drawings, forming part of this specification, and in which:

Fig. 1 is a perspective view of my improved carrying case in open position, as it appears when empty;

Fig. 2 is a perspective view of one of the individual tie holders which I employ;

Fig. 3 is a plan view showing the carrying case with one or more holders in position therein;

Fig. 4 is a transverse section on an enlarged scale substantially on the line 4—4 of Fig. 3, looking in the direction of the arrows, and

Fig. 5 is a fragmentary perspective view on a still larger scale showing one of the special spring hinges which I employ.

Referring to the drawings in detail, my improved carrying case comprises bottom and top sections 1 and 2 united along one longitudinal edge by means of hinges 3. The sections 1 and 2 are in the nature of shallow trays and are preferably formed with pointed ends 1a and 2a conforming in general with the shape of the individual holders, as shown in Fig. 3.

Positioned along but spaced from the wall of the bottom section adjacent the hinges are a series of rigid upstanding studs or posts 4, the purpose of which will hereinafter appear.

Referring now more particularly to Fig. 2, I provide a plurality of individual tie holders, such as illustrated, each holder consisting of a bottom plate or leaf 5 and a top plate or leaf 6 of the

same size and contour, these leaves being connected along one longitudinal edge by means of spring hinges 7.

Referring to Fig. 5 it will be seen that each hinge comprises a pair of angular members 8 and 9 having their horizontal flanges 8a and 9a secured as by riveting to the lower and upper faces of the bottom and top leaves 5 and 6 respectively.

The vertical flanges of the hinge members 8 and 9 extend along the edges of the leaves 5 and 6 and are provided at each end with outwardly bent ears 8b and 9b having registering openings through which passes a pivot pin 10. A wire spring 11 is wound around this pin and has its free ends bearing against the members 8 and 9 respectively, as indicated at 11a.

By virtue of the angular shape of the hinge members, it will be seen that the hinges serve to maintain the leaves 5 and 6 in spaced relation, so that when a tie is inserted between them they are substantially parallel.

Referring again to Fig. 2, it will be seen that a series of eyes 12 is formed along the longitudinal edge of the bottom leaf 5 adjacent the hinges 7. These eyes project rearwardly from this leaf and lie in a common plane parallel to that of the holder. In order to properly space the holders in the carrying case, the thickness of the eyes is increased by securing blocks 13 to the lower surface of the parts 12, and a vertical opening extends through the combined thickness of the parts 12 and 13, this opening being approximately the same in size and shape as the posts 4. While I have shown the eyes as made up of two parts 12 and 13, it will of course be understood that if the leaf 5 is molded from plastic material the eyes will be molded integral therewith, all in one piece.

It will now be obvious that a plurality of individual holders such as shown in Fig. 2 may be stacked in the carrying case by slipping the eyes of each holder down over the posts 4, thus anchoring the holders in the carrying case. While the holders are thus securely anchored against movement, they may obviously be readily detached and disengaged from the posts by a simple lifting movement.

In practice, a tie folded transversely across its middle is placed in each holder. It may be inserted in the holder by simply swinging the upper leaf away from the lower leaf against the tension of the springs in the hinges 7. When the tie is in position, and the upper leaf released, these springs urge the two leaves together, which thus constitute a press for keeping the tie smooth

and free from wrinkles at all times. The upper leaf is preferably cut away as shown in Figs. 2 and 3 leaving, in addition to the pointed end, only an intermediate portion 6a and opposite end portion 6b. These portions are united by the longitudinally extending portion 6c to which the hinges are secured. The purpose of thus cutting away the upper leaf is both to lighten the construction and also render the tie clearly visible at all times.

Fig. 4 shows three such individual holders assembled in the case with their eyes threaded over the posts 4. When it is desired to remove a tie, the holders are simply lifted out of the case, the desired tie selected, and this tie then removed from its holder by swinging open the upper leaf, as indicated in dotted lines.

What I claim is:

1. A tie carrier comprising a case made up of top and bottom sections, hingedly united, a plurality of posts rigidly carried by and projecting up from said bottom section at points spaced laterally from said hinge, and a series of individual elongated, flat tie holders shaped to fit within said case and lie one upon the other, each of said holders having along one longitudinal edge a plurality of eyes lying in a common plane parallel with that of the holder and constructed and positioned to freely slide over said posts.

2. A tie carrier comprising a case made up of top and bottom sections, hingedly united, a plurality of posts rigidly carried by and projecting up from said bottom section, and a series of individual elongated tie holders shaped to fit with-

in said case, each holder comprising a pair of leaves hingedly connected along one longitudinal edge, one of said leaves having along its hinged edge means for removably engaging said posts.

3. A tie carrier comprising a case made up of top and bottom sections, hingedly united, a plurality of posts rigidly carried by and projecting up from said bottom section at points spaced laterally from said hinge, and a series of individual elongated tie holders shaped to fit within said case, each holder comprising a pair of leaves connected along one longitudinal edge by a plurality of spring hinges, one of said leaves having along its hinged edge means for removably engaging said posts.
